US00D497550S1

(12) **United States Design Patent** (10) Patent No.: **US D497,550 S**
Halfacre et al. (45) Date of Patent: **** Oct. 26, 2004**

(54) **BEVERAGE CONTAINER**

(75) Inventors: **J. Wayne Halfacre**, New Fairfield, CT (US); **John S. Gruver**, New Canaan, CT (US); **Christian Randhahn**, Bethel, CT (US); **Charles A. Curtiss**, Norwalk, CT (US); **Stuart Leslie**, Larchmont, NY (US); **Christopher J. Matice**, Bellbrook, OH (US)

(73) Assignee: **Nestle Waters North America, Inc.**, Greenwich, CT (US)

(**) Term: **14 Years**

(21) Appl. No.: **29/192,509**

(22) Filed: **Oct. 24, 2003**

(57) **CLAIM**

The ornamental design for a beverage container, as shown and described.

DESCRIPTION

FIG. 1 is a top, front, left perspective view of a beverage container showing our new design;

FIG. 2 is a right side elevational view thereof, the left side being a mirror image;

FIG. 3 is a top plan view thereof;

FIG. 4 is a front elevational view thereof;

FIG. 5 is a rear elevational view thereof; and,

FIG. 6 is a bottom view thereof.

The broken line showing of the environment is for illustrative purposes only and forms no part of the claimed design.
